UNITED STATES PATENT OFFICE

2,452,490

CONTINUOUSLY VARIABLE INDUCTANCE

Charles Edward Payne, London, England, assignor to The Hartford National Bank and Trust Company, Hartford, Conn., as trustee

Application November 3, 1944, Serial No. 561,816
In Great Britain June 22, 1943

Section 1, Public Law 690, August 8, 1946
Patent expires June 22, 1963

4 Claims. (Cl. 171—242)

1

This invention relates to continuously variable inductances, and like electrical apparatus in which electrical contact has to be produced between a contact member and any selected part of the length of a conductor forming the inductance or the like. The conductor is usually in the form of a wire wound as an open helix and the contact member is caused to move along the helix.

According to the present invention in such apparatus the contact member is in the form of a roller which in its movement lengthwise of the conductor is constrained to rotate at a speed different from that corresponding to a simple rolling movement on the conductor. In this way a continuously wiped contact with a continuous presentation of a fresh working surface on the contact member is ensured during the adjustment of the inductance or the like.

Preferably the contact roller is driven from the means causing its movement relative to the inductance. Thus for example the helical conductor of the inductance may be caused to rotate about the axis of the helix and the contact roller which has a V groove engaging the conductor, may be slidable along a squared shaft mounted parallel to the axis of the helix and driven from the helix by suitable gearing or by a belt or friction drive.

In order that the invention may be more readily understood and carried into effect it will now be described with reference to the accompanying drawing in which:

Fig. 1 is an end view of a variable inductance unit in accordance with the invention illustrating one form of driving arrangement for the roller;

Fig. 2 is a longitudinal section of the coil shown in Fig. 1 illustrating the construction for assuring positive and continuous contact between the coil and the rolling contact; and

Fig. 3 illustrates an alternative construction of the driving arrangement for the roller.

Referring first to Fig. 1, the apparatus comprises a rigid framework consisting of two end plates 1 secured in fixed relationship by connecting rods 2. Journalled in bearings in the end plates 1 is a shaft 3 carrying a cylindrical former or drum 4 which is coaxial with the shaft. Wound on the drum 4 in the form of an open helix is a wire 5 the ends of which are connected in known manner to contact wheels 7 (only one of which is visible in Fig. 1). These wheels rotate with the drum 4 and the shaft 3 but are insulated from the latter. Contact to the wheels 7 is established by springs 6 secured on terminal

2

posts 8 to which connecting leads 9 are attached.

Contact with any desired point of the helix 5 is established by a grooved roller 10 which slides on and rotates with a squared shaft 11 which extends parallel to the shaft 3. The shaft 11 is carried in insulating bearings in a pair of levers 12 which are fixed on a pivot shaft 13 extending between and carried by bearings in the end plates 1. The electrical connection to the roller 10 is obtained by means of contact wheels 16, springs 15, terminal posts 17 and leads 18, corresponding to the wheels 7, springs 6, terminal posts 8 and leads 9 associated with the drum 4.

To maintain suitable contact pressure between the roller 10 and the wire helix 5, the levers 12 are loaded by springs 14 so that eccentricities such as arise in manufacturing practice are automatically compensated.

During rotation of the drum 4, the contact roller 10 is constrained by the engagement of its grooved periphery with the wire 5 to slide lengthwise of the shaft 11. According to the present invention, the roller 10 is also constrained to rotate during rotation of the drum 4 at a speed different from that corresponding to a simple rolling movement along the wire 5. In Fig. 1, a pulley 19 on the shaft 3 is coupled with a pulley 20 on the shaft 11 by means of a belt 21, the dimensions of the pulleys being so chosen in the case of Fig. 1 in relation to the diameters of the drum 4 and roller 10 as to cause the roller to have a higher peripheral speed than the drum. In this way a wiping contact is obtained with a constantly fresh surface of the roller 10 coming into operation, thereby enabling a satisfactory electrical contact to be produced with a minimum of wear and a minimal contact pressure between roller 10 and wire 5. It will be apparent that precisely the same effect can be achieved by driving the roller 10 at a higher peripheral speed than the drum 4.

As shown, both the shaft 3 and the shaft 11 extend through and beyond the right hand end plate 1. Consequently, owing to the different diameters 45 of the drum 4 and the roller 10, a rapid adjustment can be obtained by rotating the shaft 3, and fine adjustment by rotating the shaft 11.

In the modification shown in Fig. 3 those parts which correspond with those already described 50 with reference to Fig. 1 are indicated by the same reference numerals as in Fig. 1 and will not be further described. The construction of Fig. 2 differs from that of Fig. 1 principally in that a gear train is employed for coupling the drum 4 with the roller 10. The gear wheel 23 fast on the shaft

3 drives the wheel 26 fast on the shaft 11 by way of the intermediate wheels 24, 25, the transmission ratio for the gear train shown being such that the roller 10 has a higher peripheral speed than the drum 4. The shaft 11 in Fig. 2 does not extend through the end plate 1 but fine adjustment is performed by means of the shaft 27 on which the gear wheel 25 is secured. This shaft 27 also serves as pivot for the levers 12, so that pivotal movement of these levers does not affect the meshing of the gears.

I claim:

1. Electrical apparatus comprising a continuous conductor mounted on a support, means rotatably mounting said support, a contact member in the form of a roller, means for causing said contact roller to traverse the length of said conductor by rotation of said support to enable the point of contact to be at any position within the length traversed by said contact roller, means for maintaining a desired contact pressure between said conductor and said roller, and driving means mechanically linking said roller to said rotatable support for constraining said roller to rotate at a speed substantially different from that corresponding to a simple rolling movement on said conductor when said rotatable support is rotated whereby an effective wiping contact between said roller and said continuous conductor is obtained during operation of the electrical apparatus.

2. Electrical apparatus comprising a continuous conductor disposed in the form of an open wound helix, means for supporting said open wound helix, means rotatably mounting said supporting means, a contact roller engaging said conductor means for causing relative movement between said helix and said roller so that said roller traverses the length of said helix upon rotation of said supporting means, means for maintaining a desired contact pressure between said conductor and said roller, and driving means mechanically linking said roller to said rotatable supporting means for constraining said roller to rotate at a speed substantially different from that corresponding to a simple rolling movement on said conductor when said rotatably supporting means is rotated whereby an effective wiping contact between said roller and said continuous

4 conductor is obtained during operation of the electrical apparatus.

3. Electrical apparatus comprising a continuous wire conductor wound in the form of an open helix on a cylindrical support mounted for rotation about its axis, a contact roller with a grooved periphery engaging said wire and mounted for rotation with and translation along a shaft extending parallel to the axis of said cylindrical support, self-adjusting resilient means for imparting an approximately constant contact pressure between said conductor and said roller, and driving means mechanically linking said roller to said cylindrical support for constraining said roller to rotate at a speed substantially different from that corresponding to a simple rolling movement on said wire when said cylindrical support is rotated whereby an effective wiping contact between said roller and said wire is obtained during operation of the electrical apparatus.

4. Electrical apparatus comprising a continuous wire conductor wound in the form of an open helix on a cylindrical support mounted for rotation about its axis, a contact roller with a grooved periphery engaging said wire and mounted for rotation with and translation along a shaft extending parallel to the axis of said cylindrical support, spring-controlled means for maintaining a contact pressure between said conductor and said roller, a driving connection between said cylinder and said shaft for constraining said roller to rotate at a linear peripheral speed substantially different from the linear peripheral speed of said cylinder, and means for imparting rotation to one of said rotatable elements whereby an effective wiping contact between said roller and said wire is obtained during operation of the electrical apparatus.
